UNITED STATES PATENT OFFICE.

JOHN R. LOWREY, OF OMAHA, NEBRASKA.

STEAM-BOILER.

SPECIFICATION forming part of Letters Patent No. 769,754, dated September 13, 1904.

Application filed January 5, 1903. Serial No. 137,981. (No model.)

To all whom it may concern:

Be it known that I, JOHN R. LOWREY, residing at Omaha, in the county of Douglas and State of Nebraska, have invented certain useful Improvements in Steam-Boilers; and I do hereby declare that the following is a full, clear, and exact description of the invention, such as will enable others skilled in the art to which it appertains to make and use the same, reference being had to the accompanying drawing, which forms a part of this specification.

This invention relates to a new and useful improvement in steam-boilers, the aim of my invention being to provide a means to prevent the uneven expansion and contraction of the flue and flue-sheets, as will be described more fully hereinafter.

In the accompanying drawing I have shown a sectional view, with portions removed, of one end of a flue-sheet and connected flues, disclosing a broken portion of the baffle-plate as used in my invention.

In boiler construction, especially in that class relating to locomotive-boilers, it is an exceedingly difficult matter to prevent the ends of the flues from becoming detached from the flue-sheet, and so cause a leakage. This is primarily due to the uneven expansion and contraction of the projecting flue ends. In order to prevent this unequal expansion and contraction, I provide the ordinary flue-sheet A, provided with the flues *a* upon the rear—that is, at the end within the fire-box—with a baffle-plate B, this plate being secured by means of suitable bolts C, upon which is threaded the conical bur *b*, working into a conical seating of the baffle-plate, as shown. The flues *a* are provided with the usual bead 1 upon the inside and the usual exterior bead 2. To protect the ends of these flues *a* within the fire-box, I provide the baffle-plate B, preferably of a size equal to the inner surface or face of

the boiler, and this baffle-plate is provided with a plurality of bushings D, which bushings enter the inner ends of the flues *a*, as shown in the drawing. By this arrangement I provide the boiler with a curtain upon the end within the fire-box, and so provide an air-space *x* between the baffle-plate and flue-sheet, while the ends of the flues are further shielded and protected by the bushings D within the same. These bushings are secured by any suitable means to the baffle-plate B and, if desired, may be beaded into the flue ends *a*. In actual practice it is found that this space between the flue-sheet A and baffle-plate B becomes filled with fine cinder particles and ashes, which pack between the plates and form a sort of non-conducting filler between the plate and sheet. If desired, practically the same results may be obtained in permitting a portion of the flues *a* to project and secure to the ends thereof a suitable baffle-plate.

As the baffle-plate and the bushings are required to be renewed it is simply necessary to remove the burs *b* and place a new baffle-sheet, with connected bushings, and possibly replace a bur or two.

What I desire to secure by United States Letters Patent is—

The combination with a boiler provided with the usual flue-sheet and flues, of a perforated baffle-plate suitably secured adjacent said flue-sheet, and a plurality of bushings secured within the perforations of said baffle-plate, said bushings coinciding with and extending into said flues substantially as and for the purpose set forth.

In testimony whereof I affix my signature in presence of two witnesses.

JOHN R. LOWREY.
